C. B. BENSON.
TONGUE DEPRESSOR.
APPLICATION FILED MAR. 1, 1909.

Patented May 18, 1909

UNITED STATES PATENT OFFICE.

CHARLES BURWELL BENSON, OF TIPPECANOE CITY, OHIO.

TONGUE-DEPRESSOR.

No. 922,078.

Specification of Letters Patent.

Patented May 18, 1900.

Application filed March 1, 1909. Serial No. 480,495.

To all whom it may concern:

Be it known that I, CHARLES B. BENSON, residing at Tippecanoe City, in the county of Miami and State of Ohio, have invented certain new and useful Improvements in Tongue-Depressors, of which the following is a specification.

My invention relates to certain new and useful improvements in tongue depressors for physicians' use and it primarily has for its object to provide a tongue depressor having provisions for supporting a mirror and lamp bulb whereby light may be reflected into the patient's throat while the tongue is being held down for purposes of examination of the throat.

Generically, the invention comprises a wire tongue depressor formed of two sections hingedly connected together with means for limiting the hinged movement in one direction, and means carried by one of the hinged members for embracing a rod that carries the mirror and lamp, the embracing means being adjustable along the member so that the light may be properly reflected.

In its more detail nature the invention embodies those novel details of construction, combination and arrangement of parts all of which will be first described, and then be specifically pointed out in the appended claims, reference being had to the accompanying drawings, in which:

Figure 1, is a perspective view showing the application of my invention. Fig. 2, is a sectional view showing the application of my invention. Fig. 3, is a perspective view of the tongue depressor, *per se*, showing the slideable clip that holds the lamp and mirror rod. Fig. 4, is a cross section on the line 4—4 of Fig. 2.

Referring now to the accompanying drawings, in which like numerals and letters of reference indicate like parts in all of the figures, 1 designates the tongue depressor which comprises the tongue engaging member 1^a formed of a U-shaped wire piece, the ends of which terminate in loops 1^b, as shown. The second hinged member 2 is also formed of wire bent into a U-shape and terminating with its ends bent in opposing hook-like members 2^a, having portions 2^b to receive the loop or eye members 1^b of the section and having other portions 2^c to act as stops to limit the hinge movement of the sections so that when the instrument is applied to the

patient's tongue, the members 1 and 2 may be held at substantially right angles to one another.

On the member 2 is a sliding clip or carriage 3 which may be adjusted up and down, 60 the member 2 and carriage 3 consisting of a loop 3^a having bearing ends 3^b joined by a bridge piece 3^c, as shown. The member 2 of the tongue depressor at its lower or loop end is formed with a depression 2^x to form a 65 seat for the lamp carrying rod 4 which is adapted to slide through the loop 3 and lie parallel with the member 2, the lamp carrying rod 4 terminating at one end in a lamp bulb 4^a and having provisions 4^b at the other 70 end, by means of which the lamp may be connected in an electric circuit for purposes of energizing the same. The rod 4 is also provided with a holder 4^c for the mirror 6. By turning the rod 4 in its bearing, the light may 75 be directed to any part of the patient's throat.

From the foregoing taken in connection with the accompanying drawings, it is thought the complete construction, operation and advantages of my invention will be 80 readily understood by those skilled in the art to which my invention appertains.

What I claim is:

1. A tongue depressor comprising a pair of wire members hingedly secured together, 85 one of said members having a depressed rod receiving portion, a sliding carriage mounted on said last named member and adapted to receive a rod and coöperate with the depression in said member. 90

2. A tongue depressor comprising a pair of wire sections hinged together, a carriage mounted on one of said members, said carriage adapted to receive a light carrying rod or other instrument. 95

3. A tongue depressor comprising a pair of wire sections hinged together, a carriage mounted on one of said members, said carriage adapted to receive a light carrying rod or other instrument, said carriage comprising 100 a member having a tubular portion terminating in wire engaging clip ends to embrace the wire of the tongue depressor, substantially as shown and described.

4. A tongue depressor comprising a pair 105 of wire sections hinged together, a carriage mounted on one of said members, said carriage adapted to receive a light carrying rod or other instrument, said carriage comprising a member having a tubular portion terminat- 110

ing in wire engaging clip ends to embrace the wire of the tongue depressor, and a bridge piece connecting said ends together.

5. A surgeon's instrument comprising a tongue depressor, consisting of a pair of hinged sections, a carriage mounted on one of said sections, a light carrying rod carried

by said carriage, and a mirror carried by the rod for focusing the light.

CHARLES BURWELL BENSON.
